(57) **CLAIM**

The ornamental design for the high-fidelity noise-excluding earphone with ergonomically designed construction, as shown and described.

DESCRIPTION

FIG. 1 is a perspective view of a high-fidelity noise-excluding earphones with ergonomically designed construction showing our new design;

FIG. 2 is a perspective view thereof;

FIG. 3 is a side elevation view of the embodiment of FIG. 1.

FIG. 4 is a bottom plan view of the embodiment of FIG. 1.

FIG. 5 is another side elevation view of the embodiment of FIG. 1.

FIG. 6 is a rear elevation view of the embodiment of FIG. 1.

FIG. 7 is an insertion end elevation view of the embodiment of FIG. 1; and,

FIG. 8 is a top plan view of the embodiment of FIG. 1.
